UNITED STATES PATENT OFFICE.

EDWARD J. ZAHNER, OF CANTON, OHIO.

SHEET-METAL HOUSE.

1,253,764.

Specification of Letters Patent. Patented Jan. 15, 1918.

Application filed August 1, 1917. Serial No. 183,830.

To all whom it may concern:

Be it known that I, EDWARD J. ZAHNER, a citizen of the United States, residing at Canton, in the county of Stark and State of Ohio, have invented a new and useful Sheet-Metal House, of which the following is a specification.

The present invention relates to sheet metal buildings and has more especial reference to a building provided with a double wall, the inner wall being spaced from the outer wall and provided at intervals with ventilating apertures or spaces at its lower edge, the outer wall being provided with any suitable ventilating aperture in the upper portion of the building.

The object of the present invention is the provision of a sheet metal building provided with inner and outer spaced walls provision being made for allowing ventilation between said walls in order to provide the inner wall from becoming heated to any great extent during warm weather and to prevent the same from becoming unduly chilled in cold weather.

A further object is the provision of a sheet metal building of the character mentioned comprising inner and outer spaced walls, the inner wall being provided with suitable ventilating apertures or spaces at a point adjacent the floor and the outer wall being provided with suitable apertures or spaces at the upper portion of the building allowing a continual circulation of air between the walls in order to prevent the inner wall from becoming unnecessarily heated in hot weather and to keep the same from becoming unnecessarily cooled in cold weather, thus maintaining the temperature of the interior of the building at a proper degree.

With these objects in view the invention consists in the novel construction and arrangement of parts, hereinafter described, illustrated in the accompanying drawings, and particularly pointed out in the appended claims, it being understood that various changes in the form, proportion, size and minor details of construction may be made within the scope of the appended claims, without departing from the spirit or sacrificing any of the advantages of the invention.

In the accompanying drawings:

Figure 1 is a vertical transverse sectional view through a sheet metal building constructed in accordance with my invention.

Fig. 2 is an elevation of a portion of a rib and fragments of two adjacent sheets showing the clip for attaching the sheets to the rib.

Fig. 3 is a section on the line 3—3, Fig. 2.

Fig. 4 is a section on the line 4—4, Fig. 2.

Fig. 5 is a detail perspective view of the clip.

Fig. 6 is a fragmentary perspective view showing a portion of one of the outer rib sections.

Fig. 7 is a similar view of one of the inner rib sections.

Fig. 8 is a view partly in section showing the means of splicing the ribs.

Fig. 9 is a detail perspective view of one of the rib splicing clips.

Similar numerals of reference indicate corresponding parts throughout the several figures of the drawings.

The invention comprises generally a base upon which are mounted vertical or curved ribs between which sheet metal plates are located, said ribs and plates being preferably clamped or bound together by means of a cable extending along the entire length or width of the building and connected to each rib by means of a cable lock or the like, this cable being located at the upper extremities of the ribs while the lower extremities thereof are connected to the base in proper spaced relation by any suitable means. This much of the invention is illustrated in my copending application upon sheet metal houses filed June 22, 1917, Serial No. 176,434, and the present invention is an improvement upon the construction disclosed in said application and comprises a house constructed in the manner above briefly described and comprising spaced inner and outer walls the inner walls being provided at their lower ends with suitable ventilating apertures or spaces while the outer wall is provided adjacent the upper portion of the building with suitable apertures thus allowing a continual circulation of air between the walls.

Referring more especially to the construction illustrated in the accompanying drawings, the numeral 1 indicates the base which is anchored to the ground by suitable tie-rods 2, said base comprising the channel por-

- tion 3 having the up-turned horizontal flange 4 formed upon the upper side thereof, said flange being provided with the off-set portion 5.
- 5 The ribs are composed of the inner and outer rib sections 6 and 7 respectively which sections are interlocked as best shown in Fig. 3 of the drawings clamping the sheets 8, which form the outer wall, between the 10 two rib sections. Each inner rib section is preferably formed as best shown in Fig. 7 and comprises the channel portion 9 at the edges of which are the out-turned right angled flanges 10 having the inturned flanged portions 11 at their outer extremities, the metal from which the rib section is formed being then turned inwardly at right angles as shown at 12, beads 13 being formed in said portions 12 in order to provide a slight spring in this portion of the 20 rib section. Outwardly disposed flanges 14 are provided at the inner edges of the portions 12 and an inwardly disposed U-shaped portion 15 is provided at the extremity of each flange 14 the backwardly bent flanges 16 being provided upon each U-shaped member thus forming a pair of spaced L-shaped channels 17 arranged to receive the L-shaped portions 18 of the outer rib sections 7. Each 30 outer rib section 7 comprises the main channel portion 19 at each side of which is located a small channel portion 20 upon the inner edges of which the L-shaped portions 18 are provided.
- 35 The inner and outer rib sections are slidably connected together and the edges of the plates or sheets 8 forming the outer wall are located between said inner and outer rib sections as shown in Fig. 3. The sheets 40 or plates 21 which form the inner wall are placed against the portions 10 of the inner rib and held in engagement therewith by means of attaching clips 22 which attaching clips comprise the channel portion 23 adapted to fit snugly over the channel portion 9 of the inner rib section and the outwardly disposed flanges 24 of substantially the same width as the portions 10 of the inner rib section, the edges of the sheets 21 50 being clamped between the flanges 24 and the portions 10 of the rib section. The clips are attached to the inner rib sections by means of the curved tangs 25 which are punched inwardly from the channel portion 55 of the clip and arranged to be passed through the apertures 26 formed in the channel portion 9 of the inner rib section. These clips are located at suitable intervals upon each inner rib section in order to hold 60 the sheets 21 in position upon said rib sections.
- Each inner and outer rib is preferably formed of two or more pieces, one of which is of greater length than the other and the 65 ribs are assembled so that the splice of the inner rib sections comes at a different point from the splice of the outer rib sections. This construction is illustrated in Fig. 1 of the drawings where the inner rib section is formed of the relatively short piece A 70 and the longer piece B and the outer section composed of the relatively short piece C and the longer piece D. The abutting ends of the two pieces of the rib section are spliced by means of a splicing clip 27 which 75 comprises a plate 28 having up-turned flanges 29 at each longitudinal edge thereof and the upturned tangs 30 at opposite ends, said tangs being arranged to be inserted through suitable apertures 31 located adjacent the extremities of the rib sections and bent downwardly as shown in Fig. 8 thus splicing the rib sections. The same construction of splicing clip is used for the inner and outer rib sections except that 80 the flanges 29 and tangs 30 must obviously be turned downwardly instead of upwardly upon the splicing clips used for the outer rib sections.
- As best shown in Fig. 1 the plates 8 90 forming the outer wall extend upon each side to the base 1 while the plates 21 which comprise the inner wall terminate at a point several inches distant from the base, thus permitting air from the interior of the 95 building to pass through the space thus formed beneath the inner wall, and upwardly between the inner and outer walls, any suitable aperture, such as indicated at 32, being provided in the upper portion 100 of the outer wall for the purpose of providing proper ventilation of the building. If desired only certain of the plates 2 may terminate at the point shown in Fig. 1 while the remainder of the inner wall may 105 be extended downwardly to the base 1. By thus providing the air space between the inner and outer wall and providing means for ventilation between said walls as shown the interior of the building may be kept at 110 a lower temperature in hot weather than could be accomplished with a single wall as the air continually passing upwardly between the walls would tend to carry off the heat radiated from the outer wall and prevent the same from heating the inner wall to the same temperature as the outer wall, while in cold weather the heated air passing from the interior of the building and between the walls will have a tendency to 115 120 prevent the inner wall from becoming cooled.
- As above stated the building is preferably constructed in the manner illustrated and described in my co-pending application above referred to, the ribs and wall plates being tied together by means of the cables 33 which pass through suitable cable locks 34 carried by the ribs while the lower extremities of the ribs are properly posi- 125 130

tioned and held in position upon the base by any suitable device such as described in my co-pending application.

I claim:

- 5 1. A sheet metal building comprising spaced ribs, each rib composed of an inner and an outer section, said sections being interlocked, outer wall sheets clamped between the inner and outer rib sections, and
- 10 provided with apertures in their upper portions, and inner wall sheets attached to said inner rib sections and terminating at a distance from the ground.

2. A sheet metal building comprising spaced semicircular ribs, each rib composed of an inner and an outer section, said sections being interlocked, outer wall sheets clamped between the inner and outer rib sections and provided with apertures in their upper portions and inner wall sheets terminating at a distance from the ground and means for attaching the inner wall sheets to the said inner rib sections.

In testimony that I claim the above, I have hereunto subscribed by name.

EDWARD J. ZAHNER.
